CLAIM

The ornamental design for an insulated six-pack beverage carrier and lunch bag, substantially as shown and described.

DESCRIPTION

FIG. 1 is a top, right side, front perspective view of an insulated six-pack beverage carrier and lunch bag showing our new design;

FIG. 2 is a front elevational view thereof;

FIG. 3 is a side elevational view thereof, showing the side opposite that shown in FIG. 1;

FIG. 4 is a bottom plan view thereof;

FIG. 5 is a rear elevational view thereof;

FIG. 6 is a perspective view thereof shown in an open position; and

FIG. 7 is a top plan view thereof shown in an open position.

FIG. 1

FIG. 2

FIG. 3

FIG. 4

FIG. 5

FIG. 6

FIG. 7
